UNITED STATES PATENT OFFICE.

CHARLES T. SAMUELSON, OF NEW ORLEANS, LOUISIANA.

FLUID EJECTOR.

Application filed February 7, 1921. Serial No. 443,040.

To all whom it may concern:

Be it known that I, CHARLES T. SAMUELSON, a subject of the King of Sweden, residing at New Orleans, in the parish of Orleans and State of Louisiana, U. S. A., have invented new and useful Improvements in Fluid Ejectors, of which the following is a specification.

This invention relates to ejectors for compressing fluid, such as air, gas, vapor, or a mixture of any of them, of the type in which a motive fluid, such as steam under pressure, is allowed to entrain the fluid to be compressed.

More particularly, the invention relates to an ejector of the multi-stage type in which the resultant of the first stage, viz, the mixed compressible fluid and motive fluid is further compressed by being entrained by a second jet of motive fluid.

The object of the invention is the provision of a device of this general type having an improved, simplified and more effective arrangement of motive fluid distribution chambers, whereby a much larger motive fluid surface can be obtained than in devices heretofore known with substantially the same amount of motive fluid as is used in other ejectors.

The invention is further characterized by an improved nozzle structure which also assists in the obtainance of a large motive fluid surface with the use of a comparatively small amount of motive fluid.

The above mentioned and other objects of a more obvious character are attained by a construction embodying a plurality of concentric motive fluid distribution chambers which are provided with nozzle structures discharging into a mixing chamber having inlets for the compressible fluid. One of the distribution chambers may be employed to distribute motive fluid for the second stage and the nozzle structure of this distribution chamber extends through the mixing chamber so as to entrain the resultant of the first stage operation, namely, the mixed compressible fluid and motive fluid.

The nozzle structures used in association with the distribution chambers may all be of the same general type, and preferably are each in the form of an annular member having a plurality of circumferentially spaced independent motive fluid passages extending therethrough, each passage gradually increasing in width circumferentially of the

member, so that the several motive fluid jets gradually converge in their passage through the nozzle member and after emerging from the member may unite to form a single annular motive fluid beam.

In the accompanying drawings there is shown one form of a device in which the invention may be embodied, and in these drawings:

Fig. 1 is a top plan view of the ejector, a portion of the ejector being shown in horizontal cross section,

Fig. 2 is a vertical cross section on the line 2—2 of Fig. 1, and

Figs. 3, 4 and 5 are views showing the nozzle structures for the distribution chambers 16, 18 and 17, respectively.

Referring to the drawings more in detail, reference will be had, first, to the general construction of the ejector body which, in the illustrated embodiment of the invention, comprises a lower casing section 10 which is frusto-conical in shape, and is provided with a top flange 11 through which pass bolts 12 serving to secure the upper casing section 13 to the lower casing section, the bolts passing through a flange 14 upon the upper casing section.

The casing section 13 may be formed with a top flange 15 which extends inwardly from the peripheral wall of the section. Located within the casing 13 and below the top flange 15 are three annular concentric chambers 16, 17 and 18 having open bottoms and supported from the casing wall by webs 18'. A laterally extending inlet 19 may be provided for admitting motive fluid to each of the chambers. The distribution chamber 16 is formed by a depending annular wall 20 which affords a central opening 21 through the top casing section, and is provided at its lower end with threading 22 cooperating with a ring 23, which is held upon the wall 20 by means of threading 95 upon the inner periphery of the ring. The bottom face of the ring 23 has formed thereon webs 24 which serve to support an inverted bowl shaped centerpiece 25 extending downwardly into the lower casing section 10. 100

The outer peripheral surface of the ring 23 is inclined outwardly similarly to the inner surface of the outer wall 16' of the chamber 16. Between the wing 23 and the wall 16' is supported the nozzle member 23' shown in Fig. 3, which is placed against the wall 16' of the chamber before the ring

23 and the centerpiece 25 are placed in position; the member 23' together with ring 23 and wall 16' forming the nozzle structure.

The chamber 18, like the central chamber 16, is also formed with an open bottom, and the outer wall 19' is threaded upon its inner face to receive the nozzle supporting ring 26, the inclined inner peripheral face of which cooperates with the inclined face of the inner 10 chamber wall 27 to support the nozzle member 28 shown in Fig. 4. This nozzle member, which with the ring 26 and wall 27, forms the nozzle structure for chamber 18, is placed against the inner wall of the chamber 15 and the ring subsequently secured into position to hold the nozzle structure against the wall 27. The chambers 16 and 18 serve as reservoirs for motive fluid for the first stage operation, and the distribution chamber 20 17, located between and concentric with these distribution chambers, is intended to distribute the motive fluid for the second stage operation. The chamber 17 is also formed with an open bottom, in which are 25 threaded the nozzle supporting rings 29, 30 which are threaded to the walls of the chamber in the manner indicated in Figs. 1 and 2. Between these rings may be supported the nozzle member 31 shown in Fig. 5, the 30 nozzle member being clamped between the two rings supported from the chamber walls to form with said rings a nozzle structure for the chamber 17. It will be noted that the nozzle structure 31 extends through the 35 central portion of an annular chamber 32, which may be termed the mixing chamber. The mixing chamber 32 is formed between the peripheral wall 10 of the lower casing section and the centerpiece 25. The distribution 40 chambers 16 and 18 discharge the motive fluid into the mixing chamber through their nozzle structures, which at the same time draws thereinto the compressible fluid which passes through inlets 33 between the 45 chambers 16 and 17, inlets 34 between the chambers 17 and 18, inlets 35 around the chamber 18, and the central opening 24.

Referring to the construction of the nozzle members, Figures 3, 4 and 5 show nozzle elements which are adapted to fit between the several nozzle rings and the walls of the distribution chambers as indicated in Figure 2, but it should be understood that instead of employing separate nozzle structure as is 55 shown, the necessary passages might readily be cut in the face of the nozzle supporting rings 23, 26 and 30. However, it is often desirable to employ separate members for shaping the motive fluid jets, members of 60 satisfactory and preferable construction being shown in Figures 3, 4 and 5. Referring more particularly to Figure 5, there is shown the nozzle member for the central distribution chamber 17. This nozzle structure comprises an annular member 31 having an in-

wardly extending flange 31' adapted to fit over the upper edge of the nozzle ring 29 to be supported thereby. In its peripheral wall the nozzle member is cut away at circumferentially spaced points to form inlet openings 70 37 which lead to passages 38 gradually increasing in width circumferentially of the nozzle member so as to form jets of motive fluid which, as they pass through the nozzle member gradually converge, and after 75 emerging from the nozzle member merge to form a single annular motive fluid beam.

In Fig. 3 is shown the nozzle member 23' for the distribution chamber 16. It will be noted that this nozzle member has passages 80 23'' of the same general shape as the passages 38 of the nozzle structure for the central distribution chamber 17. However, this nozzle member is of frusto-conical shape, the passages being located in a plane parallel 85 with the plane formed by the circumference of the cone.

Figure 4 shows the shape of the nozzle member 28 for the exterior distribution chamber 18. This nozzle member is of the 90 same general annular shape as the other nozzle member and is formed with an external flange 28' adapted to rest upon the upper face of the nozzle ring 26. It is also of the same frusto-conical shape as the structure 95 23', shown in Fig. 3, and is formed with similar passages 28'' for the motive fluid jets, these passages, however, being located within the flange 28' instead of exterior thereto as in the structure shown in Figure 100 3.

In operating this ejector, motive fluid is admitted to the three distribution chambers 16, 17 and 18 by means of the inlet 19. The motive fluid from the chamber 18 issues 105 from the chamber through the independent inlets of its nozzle structure in the form of independent jets, which have a very high velocity. These jets gradually expand circumferentially of the nozzle member, and after emerging from the nozzle member merge into a single annular stream having these jet portions of very high velocity. The annular stream issuing from the nozzle member 28 is ejected across the compressible 110 fluid inlets 34 and against the outer face of the second stage nozzle outlets 38. At the same time the motive fluid from the smaller first stage distribution chamber 16 issues in a similar manner from the nozzle structure 115 against the inner face of the second stage nozzle outlets 38 in the form of an annular stream, and across the compressible fluid inlets 33 between the chambers 16 and 17. It will be obvious that the motive fluid streams 120 from the chambers 16 and 18 converge, the stream from the chamber 16 drawing compressible fluid through the inlets 33 and inlet 21 and mixing therewith in the chamber 32, the motive fluid from the chamber 18 draw- 125 130

ing compressible fluid through inlets 34, 35 and mixing therewith. The motive fluid in the second stage chamber 17 is discharged from the nozzle member 31 in advance of 5 and below the mixing chamber 32 between the side wall of the center piece 25 and the wall of the bottom casing section 10. The motive fluid from this nozzle member 31 draws downwardly the resultant of the first 10 stage operation, viz, the mixture of first stage fluid from chambers 16 and 18 and the compressible fluid that has passed through the various inlets, into the chamber, mixes with this resultant within the diffusing 15 space between the centerpiece wall and the bottom casing section, and passes through the bottom opening of the ejector below the centerpiece.

From the above description it will be observed that I have provided a very simple 20 and compact type of multi-stage ejector apparatus which affords an unusually large motive fluid surface in each of the stages with but a small consumption of motive 25 fluid, and which causes the motive fluid to issue from its distribution chambers with a very high velocity. It will, of course, be understood that the detail showing in the drawings and the above detailed description 30 are set forth merely for the purpose of conveying a thorough understanding of the invention, which is not limited to the illustrated and described embodiment thereof, but which is more clearly defined in the following claims.

What I claim is:

1. In an ejector, a nozzle structure comprising an endless series of nozzles, each nozzle having a passage for a motive fluid 40 jet provided with end walls which diverge circumferentially of the series from the inlet to the outlet of the nozzle, and lateral walls between the end walls which are substantially parallel.

45 2. In an ejector, a nozzle structure comprising a plurality of nozzles arranged in a circular series, each nozzle having a motive fluid jet passage provided with end walls which diverge from the inlet to the outlet of the nozzle circumferentially of the series, and lateral walls between the end walls which are substantially parallel.

50 3. In an ejector, a nozzle structure comprising an endless truncated-cone shaped nozzle member provided with a plurality of spaced independent passages for motive fluid jets, each passage gradually increasing in width circumferentially of the nozzle member from its inlet to its outlet, and each 55 passage being located in a plane parallel with the plane defined by the circumference of the cone.

4. Multi-stage ejector apparatus comprising a plurality of separated concentric distribution chambers for motive fluid, walls 60

separating said chambers, a nozzle structure comprising a plurality of individual fluid jet passages, in association with each of said distribution chambers, one of said distribution chambers serving to distribute motive 70 fluid for the second stage, an inlet for compressible fluid adjacent the nozzle structure for the first stage distribution chamber, a mixing chamber located in the path of said fluid, the exit opening of the nozzle structure of said second stage chamber being located in advance of said mixing chamber whereby the mixed motive and compressible fluids may be compressed by the motive fluid issuing from said second stage 75 nozzle.

5. Multi-stage ejector apparatus comprising a plurality of concentric distribution chambers for first-stage motive fluid, a nozzle structure in association with each of said distribution chambers, inlets for elastic fluid adjacent said nozzle structures, a first-stage mixing chamber, a second stage motive fluid distribution chamber concentric with said first stage chambers, a nozzle structure in 85 association with said second-stage distribution chamber and adapted to discharge motive fluid in advance of said mixing chamber to thereby compress the resultant of said 90 first-stage operation.

6. Multi-stage ejector apparatus comprising a plurality of distribution chambers for first-stage motive fluid, a nozzle structure in association with each distribution chamber, elastic fluid inlets adjacent the nozzle structures, said inlets and nozzle structures leading to a mixing chamber, a second-stage motive fluid distribution chamber substantially concentric and in substantially the same horizontal plane with said first mentioned 105 distribution chambers, a nozzle structure in association with said last-mentioned distribution chamber and extending through said mixing chamber thereby to discharge motive fluid in advance of the resultant of 110 said first stage and to compress said resultant.

7. Multi-stage ejector apparatus comprising a plurality of annular distribution chambers for first-stage motive fluid, a nozzle structure in association with each distribution chamber, elastic fluid inlets adjacent the nozzle structures, said inlets and nozzle structures leading to a mixing chamber, an annular second-stage motive fluid 115 distribution chamber, a nozzle structure in association with said last-mentioned distribution chamber and extending through said mixing chamber thereby to discharge motive fluid in advance of the resultant of said first 120 stage and to compress said resultant.

8. Multi-stage ejector apparatus comprising a plurality of annular concentric distribution chambers for first-stage motive fluid, a nozzle structure in association with each 130

distribution chamber, elastic fluid inlets adjacent the nozzle structures, said inlets and nozzle structures leading to a mixing chamber, an annular second-stage motive fluid 5 distribution chamber concentric with said first stage distribution chambers, a nozzle structure in association with said last-mentioned distribution chamber and extending through said mixing chamber thereby to 10 discharge motive fluid in advance of the resultant of said first stage and to compress said resultant.

9. Multi-stage ejector apparatus comprising a plurality of concentric distribution 15 chambers for first-stage motive fluid, a nozzle structure in association with each distribution chamber, a mixing chamber, elastic fluid inlets to said mixing chamber, said nozzle structures discharging into said mixing chamber, a distribution chamber for second stage motive fluid located between and concentric with said first-mentioned distribution chambers, a nozzle structure in association with said second stage distribution 25 chamber and extending through said mixing chamber to discharge motive fluid in advance of said mixing chamber.

10. Multi-stage ejector apparatus comprising a plurality of concentric distribution 30 chambers for first-stage motive fluid, a nozzle structure in association with each distribution chamber, a mixing chamber, elastic fluid inlets to said mixing chamber, said nozzle structures discharging into said mixing chamber, a distribution chamber for second stage motive fluid located between and concentric with said first-mentioned distribution chambers, a nozzle structure in association with said second stage distribution 35 chamber and extending through said mixing chamber to discharge motive fluid in advance of said mixing chamber.

11. Multi-stage ejector apparatus comprising a plurality of concentric distribution 45 chambers for first-stage motive fluid, concentric nozzle structure in association with said distribution chambers, a mixing chamber, elastic fluid inlets into said mixing chamber, said nozzle structures discharging motive fluid in concentric endless 50 streams into said mixing chamber, the two streams converging, a distribution chamber for second stage motive fluid concentric with and located between said first-stage distribution chambers, an endless nozzle structure in association with said second-stage chamber and extending through said mixing chamber between the converging streams from said first-stage nozzles the 55 fluid from said second stage nozzle structure serving to compress the resultant of 60 said first stage operation.

12. Multi-stage ejector apparatus comprising a plurality of concentric annular 65 distribution chambers for first-stage motive

fluid, concentric annular nozzle structures in association with said distribution chambers, a mixing chamber, elastic fluid inlets into said mixing chamber, said nozzle structures discharging motive fluid in concentric 70 annular streams into said mixing chamber, the two streams converging, an annular distribution chamber for second stage motive fluid concentric with and located between said first-stage distribution chambers, an endless annular nozzle structure in association with said second-stage chamber and extending through said mixing chamber between the converging annular streams from said first stage nozzles the fluid from 80 said second stage nozzle structure serving to compress the resultant of said first stage operation.

13. In an ejector, a motive fluid distribution chamber having an inlet opening, a 85 mixing chamber having an inlet opening for compressible fluid, said distribution chamber having an outlet opening, and a nozzle structure for delivering motive fluid jets from the distribution chamber to said mixing chamber, said nozzle structure comprising spaced walls adjacent the outlet of said distribution chamber, and means between said walls having a plurality of spaced fingers, the spaces between said fingers affording passages for the motive fluid and the fingers dividing the space between said walls into a plurality of independent nozzle passages. 90

14. In an ejector, a nozzle structure comprising spaced walls, a member supported between said walls having a plurality of separated fingers provided with passages therebetween, the fingers dividing the space between said walls into a plurality of 100 independent nozzle passages, said member being removable from between said walls. 105

15. In an ejector, a nozzle structure comprising a pair of concentric walls slightly spaced apart in the same horizontal plane, 110 an annular member supported between said walls having a plurality of fingers spaced circumferentially of said walls, said fingers having passages therebetween which serve as passageways for motive fluid jets. 115

16. In an ejector, a nozzle structure comprising a pair of concentric walls slightly spaced apart in the same horizontal plane, an annular member supported between said walls having a plurality of fingers spaced 120 circumferentially of said walls, said fingers having passages therebetween which serve as passageways for motive fluid jets, the sides of the adjacent fingers diverging to provide passages which widen circumferentially of said walls. 125

In testimony whereof I have hereunto set my hand.

CHARLES T. SAMUELSON.
